UNITED STATES PATENT OFFICE

JOHN ALTON HARRISS, OF NEW YORK, N. Y.

DESIGN FOR A PEDESTRIAN-VEHICULAR TRAFFIC SIGNAL LIGHT

Application filed April 15, 1930. Serial No. 35,252. Term of patent 14 years.

To all whom it may concern:

Be it known that I, JOHN ALTON HARRISS, a citizen of the United States, residing at New York, in the county and State of New York, have invented a new, original, and ornamental Design for a Pedestrian-Vehicular Traffic Signal Light, of which the following is a specification, reference being had to the accompanying drawing, forming part thereof.

The figure is a side elevation of a signal light, showing my new design.

The signal light has four sides each presenting the same appearance.

I claim:

The ornamental design for a pedestrian-vehicular traffic signal light, as shown and described.

In testimony whereof, I have signed my name to this specification.

JOHN ALTON HARRISS.
